COMBINED ASH TRAY AND HOLDER

Harold C. Grabfelder, Hollywood, Calif.

Application July 22, 1955, Serial No. 37,094

Term of patent 7 years

(Cl. D85—2)

FIG. 1

FIG. 2

FIG. 3

Fig. 1 is a top plan view of a combined ash tray and holder, showing my new design;

Fig. 2 is a front view thereof; and,

Fig. 3 is a side elevational view thereof.

I claim:

The ornamental design for a combined ash tray and holder, substantially as shown.
